UNITED STATES PATENT OFFICE

ALBERT F. HOFFMAN, OF NEWARK, NEW JERSEY

BOTTLING MACHINE

Application filed February 10, 1928. Serial No. 253,481.

My invention relates to improvements in the class of bottling machines in which the beverage to be bottled is maintained within a rotative chamber provided with outlets and tubes through which the beverage is discharged into the bottles in successive manner. The present invention is an improvement over the machine shown and described in U. S. Letters Patent No. 1,631,530 issued to me on 10 the 7th day of June, 1927.

In the bottling of certain beverages, especially those which are carbonated or charged with gas, it is desirable to maintain the beverage at a low temperature right down to the 15 time it is placed into the bottles, in order to prevent the waste of gas in the charged beverage. The lower the temperature maintained in the beverage down to the time the same is sealed in the bottles, the less escape 20 there is of the gas from the liquid because at low temperatures the tendency of the gas to escape from the beverage is much less than at higher temperatures. One object of the present invention, therefore, is to maintain 25 the beverage within the filling chamber of the machine at low temperature during the bottling operation and to retain it in this condition if for any reason the bottling operation should temporarily cease for a period of time. 30 One advantage of the present invention over that shown in my said patent is that the cooling coil arranged to maintain the beverage in cool condition, is composed of headers connected by a series or group of tubes, preferably in circular form, the tubes being connected to the headers in parallel relation. This divides the stream of brine or cooling fluid, so that the flow thereof may be maintained through the cooling device with lower 35 pressures. In addition, tubes having greater areas for cooling may be arranged in the machine than in the before-mentioned patented device, thereby increasing the efficiency of the cooling apparatus without necessitating rebuilding of the bottling machine as a whole. In addition, the present construction is simpler to manufacture and to install 40 in the machine.

Another object of the present invention is 45 to provide an efficient distributing mechanism

for controlling the circulation of the brine or other cooling fluid through the cooling apparatus. One object of the distributing apparatus is to reduce the lateral dimension thereof and thereby increase its efficiency and at the same time reduce the friction between the stationary and movable parts thereof. Parts of the distributing mechanism must necessarily revolve to accord with the movement of the filling machine and the cooling 55 apparatus and the smaller the diameter of these movable parts the less friction there will be as between these and the stationary parts of the distributing device. In the present construction the lateral dimension of the distributing device is much less than in the aforesaid patent. Another object of the present distributing device is to provide simple means for effectively packing the same in order to avoid leakage between the stationary and 60 revolvable parts of this apparatus. Furthermore, the pressure on the packing in the distributing device may be very easily adjusted from time to time if leakage between the parts is detected. Another object of the invention is to simplify as a whole the distributing apparatus. Other advantages will be pointed out in the following detailed description of my invention.

In the drawings forming part of this application,

Figure 1 is a side elevation of a well known type of bottling machine in which my present invention has been incorporated,

Figure 2 is a partly broken plan view of the apparatus shown in Figure 1,

Figure 3 is a vertical, sectional view taken through the center of part of the machine,

Figure 4 is a horizontal, sectional view taken on the line 4—4 of Figure 3,

Figure 5 is a view one-half of which is an elevation and one-half in vertical section, showing the distributing apparatus,

Figure 6 is a sectional view taken on the line 6—6 of Figure 5,

Figure 7 is a sectional view taken on the line 7—7 of Figure 5, and

Figure 8 is a similar view taken on the line 8—8 of Figure 5.

The bottling machine to which I have

shown my invention applied in the annexed drawings is of a well known type. It includes a rotative liquid or beverage dispensing chamber 1 below which project the bottle centering bells 2 which assist in projecting the charged beverage separately into the several bottles 20 as they travel upon the movable platforms 5a. The chamber 1 is supported on a central column 3 which is journaled to rotate upon the base 4 in well known manner. The lower member 21 which carries the several vertically movable bottle platforms 5a is provided with a gear 6 around its exterior, and this meshes with a pinion 7 on the shaft 8 by means of which the revolvable portion of the machine is operated. The shaft 8 which is shown in a vertical position is provided with a mitre gear 9 which is operated by a gear 10 arranged on a shaft which is adapted to be driven from any source of power, such as a belt operating on the pulley 11.

Compressed air is admitted through the pipe 14 to the chamber 22 where it escapes through circular drilled holes around the periphery near the bottom. The air then bubbles up through the water surrounding the tank 22 and into the upper part of the central tank 12. The pipes 13 communicating from the top of the tank 12 with the annular chamber 1, convey the air to that part of the chamber 1 above the level of the carbonated water or beverage confined in the lower part of the chamber 1. Other pipes 35 communicating with the air space in the tank 12 convey air to several parts of the filler in order to lift the valves and assist in the proper functioning of the filling machine. In general, the compressed air serves to prevent the CO₂ from escaping from the carbonated water or beverage in the chamber 1; to actuate the filling valves, and to actuate a diaphragm valve, through the medium of the float valve in the chamber 1, and thus 40 control the carbonated water or beverage level in the chamber 1. City water is placed in the tank 12 by the filler operator and remains here until drawn off by the filler operator. The difference in level inside and outside the chamber 22 is a measure of the liquid or beverage to be placed in each bottle. The parts just described, as well as other parts of the machine shown in the drawings except for those hereinafter specifically described, are 45 of usual construction, so that further detailed description thereof is unnecessary to an understanding of the operation of my present invention. The means for cooling the beverage or for maintaining it in cold condition until discharged into the bottles is placed within and is revolvable with the annular filling chamber 1. As shown in the drawings, (Figure 4) there are two headers 23, 24 arranged in the chamber 1 a short distance from each 50 other, and between these two headers are

connected a series of parallel tubes 25 of arcuate shape, arranged preferably in several horizontal rows, lying one above the other in close formation, so that these tubes extend around the major portion of the chamber 1. These tubes may be welded, brazed or otherwise secured to the vertical wall of the header 23 at one end of each tube and similarly secured to one vertical wall of the header 24 at the other end whereby the bores of all of the tubes will be in communication with the headers at the ends of the tubes. It will be apparent from this construction and disposition of the parts that brine or other cooling liquid introduced into one of these headers will circulate in multiple streams through the several tubes 25 and will thence flow into the opposite header from which it is conveyed back to the brine cooling apparatus or refrigerator (not shown). The cooling device, consisting of the headers and the tubes is so disposed in the filling chamber 1 that the beverage contained in the filling chamber rises to a level which causes the cooling device to be submerged in the beverage. Preferably there is a vertical wall 26 of annular shape, disposed in the filling chamber 1 adjacent the outer row of tubes 25 so that all of the beverage entering the filling chamber will flow over the system of tubes before entering the several filling valves 27 which control the flow of the beverage into the bottle through the filling tube.

It will be apparent that with the cooling device arranged in the charging chamber 1, it is possible to keep the beverage cold until it discharges into the several bottles, and in this manner it is possible to reduce to a minimum the loss of gas from the charged beverage. By arranging the headers 23, 24 connected with the several tubes 25 in multiple relation, the cooling fluid may be circulated through the cooling apparatus with a minimum pressure. Furthermore, with the arrangement of the tubes, as shown herein, a greater tube surface may be provided than in the construction shown in my aforesaid patent for increasing the efficiency of the cooling device without increasing the size of the filling chamber 1.

The remainder of the present invention relates to the distributing apparatus for controlling the circulation of the cooling fluid through the cooling apparatus which latter as above described, continually rotates while the machine is in operation. There is a pipe 28 having a lateral connection 29 which passes through the wall 30 of the filling chamber 1, and this lateral connection is connected with one of the side walls of the header 23 for the purpose of conducting the cooling liquid or brine from one end of the cooling apparatus. There is a similar pipe 31 having a lateral connection at 32 also extending through the wall 30 and connected with one wall of the

header 24 and this pipe is adapted to supply the cooling liquid or brine to this header, so that the fluid will circulate through all of the tubes 25 and then be discharged from the header 23 through the pipe 28. The pipes 28, 31 which are shown vertically disposed, are provided with horizontally extending portions near the top of the machine, and these pipes, together with the members of the distributing apparatus with which they directly connect, all revolve with the main portions of the machine.

In the drawings I have shown a series of arrows indicating the direction of flow of the cooling fluid in the several pipes and valves, but it will be understood that the direction of flow may be reversed. As shown in Figure 1 there is a pipe 33 leading from a refrigerating apparatus (not shown) which serves to cool the brine and to prepare it for passage through the cooling device above described. This pipe 33 delivers the fluid into branch pipes 34 which are directed downwardly and at the lower ends are provided with lateral branches disposed diametrically at opposite sides of the distributing device to which latter they are connected, as will be hereinafter set forth. There is a pipe 35 for conducting the cooling fluid from the present apparatus and back to the refrigerating apparatus, thereby completing the circulation of the cooling fluid as between the present cooling device and the refrigerator. This pipe 35 connects with the two downwardly extending branch pipes 36 which are also provided at their bottom ends with lateral connections disposed on opposite sides of the distributing apparatus to which they are connected and these branches are arranged preferably ninety degrees from the above described branches 34.

The distributing device is shown more in detail in Figures 5 to 8 inclusive. It consists principally of a body 37 provided at its lower end with a threaded stem 38 which is adapted to be secured by suitable nuts with the internal closing cap or head 39 which is disposed within the tank 12. The upper end of this body 37 is provided with a threaded plug or stem 40 with which there is connected the pipe 14 by means of which compressed air is introduced through the central bore 41 of the body 37 into the compression chamber 22 which corresponds with the aforesaid patent. The body 37 remains stationary or in other words it does not revolve with the main portion of the machine. It is provided with a number of ports for maintaining communication between the inlet and outlet pipes of the brine circulating system as follows: There is a lateral port 42 the outer end of which is threaded and this port communicates with a vertical port 43. There are other lateral ports 44 below and in the same vertical plane

with the port 42 and these also communicate with the vertical port 43 so that the port 42 which is in the stationary body 37 communicates with the ports 44 through the intermediate portion of the vertical port 43. The upper end of the port 43 is closed or blind, but this port is shown as extending to the lower end of the body 37 and its lower end is permanently closed by a plug 45. The portion of the port 43 which extends below the lateral port 44 serves no purpose in the functioning of the device and it is simply carried to the end of the body in order to permit the port to be drilled from one end of the body 37. At the opposite side of the body 37 I have shown a vertically arranged port 46 the upper end of which is closed and the lower end of which is closed by a permanent plug 47. This port 46 is shown as arranged one hundred and eighty degrees from or opposite the port 43 and parallel with the same. There is a lateral port 48 in the body 37 communicating with the port 46 and corresponding with the right hand port 42.

The upper end of the body 37 is provided with a flange 49 through which the bores 42, 48 extend and below this flange there is an annular ring 50 surrounding the body 37 and its internal bore is ground to fit closely to the outer surface of the body 37. This annular body 50 is adapted to revolve in relation to the stationary body 37; and in order to prevent the escape of the liquid between the surfaces of the body 37 and the ring 50 I have provided a suitable packing or stuffing. There is a ring 52 of packing or stuffing material set into a recess 53 in the upper side of the ring 50 and this is pressed downwardly and into the recess by means of a ring nut 54 which is threaded into the socket 53 of the ring member 50. On the under portion of the ring 50 there is a corresponding recess or pocket 55 in which there is compressed a packing or stuffing ring 56 by means of the ring nut 57 which is threaded into the bottom end of the socket 55. These ring nuts 54, 57 may be turned by a suitable spanner engaging in the notches 58 on the peripheries of the ring nuts to tighten the packing rings 52, 56 to any degree necessary to prevent the escape of the circulating fluid between the surfaces of the body 37 and the ring 50. The ring 50 is provided on its inner surface with an annular groove 59 extending completely around the ring and in line with the port 44 so that an annular groove 59 forms a means of communication between the port 44 and the lateral port 60 in the ring 50 at all times during the revolution of the ring 50. The lateral port 60 is threaded and to it the end of the pipe 31 is connected.

There is a second annular ring 61 arranged to fit closely but revolvable upon the outer surface of the body 37 and this ring is sim-

ilar to the ring 50. It is packed by means of a packing or stuffing ring 62 seated in the recess or pocket 64 and compressed by means of a ring nut 63 threaded into the socket 64. At the lower side of the ring 61 there is a corresponding packing or stuffing ring 65 seated in the pocket 66 and held compressed therein by means of the ring nut 67 threaded into this pocket 66. The ring nuts 63, 67 may also be turned by a suitable spanner 10 for the purpose of compressing the packing rings 62, 65 and prevent the escape of liquid between the body 37 and the ring 61. I have shown pins 68 threaded into the body 37 which are for the purpose of serving as guides to keep the rings 61 and 50 in their correct position relative to the ports 44 and 72. By removing the pins 68 the various ring nuts may be screwed out of the annular rings 61 or 50.

20 The body 37 is provided with two additional vertical ports 73, 74 both of which are closed at their upper ends and are closed at their lower ends by suitable plugs 76 and these vertical ports are disposed opposite each other and ninety degrees from the vertical ports 43, 46. It will be understood that in stating the exact locations of these ports I am merely describing the preferred construction shown and do not intend to limit the scope of my invention to the precise arrangement described. In the upper end of the body 37 there is a lateral port 77 which communicates with the vertical port 73 and its outer end is threaded. In the opposite side of the body 37 there is also a lateral port 78 communicating with the vertical port 74 and its outer end is also threaded. The outlet pipes 36 are threaded into the ports 77, 78 so that these pipes receive fluid which rises in the vertical ports 73, 74. The inlet pipes 34 are threaded into the ends of the lateral ports 42, 48 so that the fluid from the inlet pipe 33 is fed into the vertical ports 43, 46.

Operation

When the machine is in operation, the cooling liquid or brine is circulating continuously through the tubes 25 and the headers 23, 24 to cool the beverage contained in the distributing chamber 1. The cooling device including the pipes 25 revolve with the machine; and as the pipes 28, 31 revolve they cause the rings 50, 61 to revolve with them. The cooling fluid coming to the machine through the pipe 33 divides and passes through the pipes 34 and from there through the lateral ports 42, 48 in the body 37 and into the vertical ports 43, 46. When the fluid has filled these vertical ports 43, 46 the fluid in the lower portions of these ports will become static and there will be a flow of the fluid out through the lateral ports 44 into the annular space 59 in the revolvable ring

50. From this annular space 59 the liquid will flow through the port 60 into the pipe 31 and the latter will conduct it through the inlet head 24 of the cooling apparatus. From this head the fluid will circulate through the several tubes 25 to the opposite header 23 and from there it will flow into the pipe 28, through the port 70 and into the annular chamber 71 in the revolving ring 61. From this annular chamber the fluid will pass 70 through the lateral ports 72 into both vertical ports 73, 74. It will pass upwardly in these vertical ports and thence into the branch pipes 36 which are joined to the common outlet pipe 35 which returns the fluid to the refrigerating apparatus (not shown). As the annular space 71 in the ring 61 is always in communication with the lateral port 70 the fluid will pass through the lateral and vertical ports 72, 73, 74 from the inlet pipe 28 to the outlet pipe 35, regardless of the position of the ring 61 in relation to the body 37. Likewise, the annular space 59 in the ring 50 is in communication at all times with the lateral bore 44 so that the fluid from the refrigerating device through the pipe 33 will flow to the annular space 59 through the lateral ports 44 and the vertical ports 43, 46 regardless of the position of the ring 50 on the body 37. From this it will be apparent that a continuous circulation of the fluid through the distributing device may be maintained during the revolution of the machine. In the present construction the surfaces which revolve in contact with stationary surfaces, to wit, the inner surface of the rings 50, 61 and the outer surface of the body 37 may be of less diameter than in the construction shown in my aforesaid patent, and therefore the friction between the moving and stationary parts is reduced to a minimum, so that the moving parts may turn more easily than in the aforesaid construction. This arrangement also permits the use of packing or stuffing rings with tightening nuts, as shown herein, and this type of packing may be kept in proper working condition with the least attention.

It will be noted that the vertical ports 43, 46 both serve the same purpose and the vertical ports 73, 74 also serve the same purpose, and it will be feasible to eliminate one of each of these vertical ports and still maintain the same circuit for the cooling fluid. However, I prefer to duplicate these ports in order to secure sufficient volume of flow in the distributing device and still retain a minimum lateral dimension for this device.

Having described my invention, what I claim is:

1. A bottling machine comprising a rotatable chamber for holding a supply of liquid for the filling operation, and a cooling device associated with the chamber to rotate therewith and comprising headers, a plu- 120

rality of tubes connected at opposite ends to the respective headers in multiple relation, and means for introducing cooling liquid into one of said headers and for withdrawing it from the other, to cause a circulation of the cooling fluid through said tubes.

5 2. A bottling machine comprising a rotative chamber of annular shape for holding a supply of liquid for the filling operation, and an annularly shaped cooling device associated with the chamber to rotate therewith, and comprising headers, a plurality of tubes connected at opposite ends to the headers in multiple relation, and means for introducing cooling fluid into one of said headers and for withdrawing it from the other, to cause circulation of the cooling fluid through said tubes.

10 3. A bottling machine comprising a rotative annular chamber for holding a supply of liquid for the filling operation, a plurality of members for discharging the liquid from said chamber into receptacles, a cooling device arranged within said annular chamber to rotate therewith and comprising headers, a plurality of tubes connected at opposite ends to the respective headers in multiple relation, means for introducing cooling fluid into one of said headers and for withdrawing it from the other, and an overflow wall in said chamber adjacent said tubes whereby the cooling fluid around said cooling device will overflow said wall in passing to said discharging means.

15 4. A bottling machine comprising a rotative chamber for holding a supply of liquid for the filling operation, a cooling device associated with the chamber to rotate therewith, and means for controlling the circulation of cooling fluid in said cooling device, comprising a vertically arranged body having a plurality of lateral ports connected by a vertical port, a fluid pipe connected with one of said lateral ports of said body, a member revolvable in relation to said body and having a port communicating with another of said lateral ports, said body having other lateral ports connected by a vertical port, a fluid pipe connected with one of said last mentioned

20 50 lateral ports and a second member revolvable in relation to said body and having a port registering with one of said last mentioned lateral ports, and pipes connected with said revolvable members for conducting the cooling fluid to and from said cooling device.

25 5. A bottling machine comprising a rotative chamber for holding a supply of liquid for the filling operation, a cooling device associated with the chamber to rotate therewith, and means for controlling the circulation of cooling fluid in said cooling device, and comprising a vertically arranged body having a plurality of lateral ports therein and having vertical ports connecting certain

30 55 60 65 70 75 80 85 90 95 100 105 110 115 120 125 130 around said body and having an annular chamber registering with the lateral ports in said body, and a pipe connected with said revolvable member and communicating with said annular chamber, said pipe being connected with said cooling device.

6. A bottling machine comprising a rotative chamber for holding a supply of liquid for the filling operation, a cooling device associated with the chamber to rotate therewith, and means for controlling the circulation of cooling fluid in said cooling device, and comprising a vertically arranged body having a plurality of lateral ports therein and a plurality of vertical ports connecting certain of said lateral ports to each other, a plurality of members disposed one above the other and revolvable about said body, each of said revolvable members having an annular chamber continuously communicating with certain of the lateral ports of said body, and pipes connected with said revolvable members and communicating with said annular chambers for conducting the cooling fluid to and from said cooling device.

7. A bottling machine comprising a rotative chamber for holding a supply of liquid for the filling operation, a cooling device associated with the chamber to rotate therewith, and means for controlling the circulation of cooling fluid in said cooling device, and comprising a vertically arranged body disposed centrally of said chamber and having a plurality of lateral ports therein, a plurality of vertically disposed parts arranged at different sides of the axis of said body and connecting certain of said lateral ports with each other, a plurality of members arranged vertically, one above the other, to revolve in relation to said body, and having annular chambers each communicating continuously with certain of said ports, and pipes connected with said revolvable members for conducting the cooling fluid to and from said cooling device.

8. A bottling machine comprising a rotative chamber for holding a supply of liquid for the filling operation, a cooling device associated with the chamber to rotate therewith, and means for controlling the circulation of cooling fluid in said cooling device, and comprising a vertically arranged body having a plurality of lateral ports therein and vertical ports connecting certain of said lateral ports with each other, a plurality of members revolvable around said body, each having an annular chamber communicating with certain of the lateral ports of said body, packing rings between said body and said revolvable members on each side of said annular chambers, and nuts for tightening said rings and pipes connected with said revolvable members and communicating with said annular chambers, said pipes being connected with said cooling device.

9. A bottling machine including a rotative chamber for holding a supply of liquid for the filling operation, a cooling device associated with the chamber to rotate therewith and means for controlling the circulation of cooling fluid in said cooling device including a vertically arranged body disposed centrally of said chamber and having a plurality of lateral ports therein, said body having a plurality of vertical ports connecting certain of said lateral ports with each other, a plurality of other vertical ports connecting other of said lateral ports with each other, members revolvable in relation to said body and having annular chambers continuously communicating each with different lateral ports, supply and discharge pipes connected with said revolvable members and with said cooling device to cause the circulation of liquid in the latter, said pipes being in communication with the annular chambers of said revolvable members, said body having a plurality of lateral ports connected respectively with the several sets of vertical ports and a plurality of supply and discharge pipes connected with said last mentioned lateral ports to supply liquid to and discharge it from said body.

Signed at the city of Newark, county of Essex and State of New Jersey this 27th day of January, 1928.

ALBERT F. HOFFMAN.
